UNITED STATES PATENT OFFICE.

JAY E. CRANDALL, OF CHICAGO, AND ALBERT OLGAY, OF GLEN ELLYN, ILLINOIS.

HUMIDIFIER FOR GAS ENGINES.

Application filed September 12, 1921. Serial No. 500,186.

To all whom it may concern:

Be it known that we, JAY E. CRANDALL and ALBERT OLGAY, citizens of the United States, and residing at Chicago, Illinois, and 5 Glen Ellyn, Illinois, respectively, have invented new and useful Improvements in Humidifiers for Gas Engines, of which the following is a specification.

This invention relates to a humidifier for 10 gas engines by which water vapor may be delivered to the intake manifold of the engine.

We are aware that it has heretofore been proposed to deliver water vapor to the manifolds of gas engines, but such delivery is not 15 desirable, either when the engine is cold or when it is running at very slow speeds, for the reason that under both of these conditions a rich fuel mixture is required and since the water vapor reduces the richness of 20 the mixture, the vapor should be employed only after the engine has been heated up and when it is running at least normal speed.

One of the primary purposes of our invention, therefore, is to provide a humidifier 25 which will deliver water vapor in requisite quantities to the intake manifold when it is desirable, but which will be thermostatically controlled so that vapor will not be delivered until the engine reaches a predetermined 30 temperature, and which will also be controlled by manipulation of the throttle so that vapor will not be admitted when the engine is running at low speeds.

Another object of our invention is to provide a humidifier which will be simple in 35 construction, economical to manufacture, easy to install, and one which will not be liable to get out of order but will be efficient and durable for prolonged periods of time.

40 Other objects and many of the inherent advantages of our invention should be readily appreciated as the same becomes better understood by reference to the following description when considered in connection with 45 the accompanying drawings.

Referring to the drawings:

Fig. 1 is a side elevation of a gas engine equipped with our invention;

Fig. 2 is an enlarged elevation of our im- 50 proved humidifier looking toward the left of Fig. 1;

Fig. 3 is a similar view looking toward the left of Fig. 2;

Fig. 4 is a bottom view of the humidifier;

Fig. 5 is a detail of the atomizing nozzle; 55 and

Fig. 6 is an enlarged fragmentary view showing the connection with the intake manifold.

While our invention may be applied to 60 any type of gas engine, we have shown in Fig. 1 for purposes of illustration merely, a well known type of engine including the intake manifold 7, the throttle control rod 8, and the water circulating pipes 9 and 11 of 65 the water cooling system. These parts, as well as other parts of the engine, may be of any well known or preferred construction.

The humidifier proper comprises a casing 70 12 cored out to provide a lower water receptacle 13 and an upper chamber 14, the chamber and receptacle being connected by a passage 15, the effective area of which may be regulated by an adjustable needle valve 16. An air passage 17 also communicates through 75 a lateral branch 18 with the chamber 14 and the effective area of this passage is likewise controlled by an adjustable needle valve 19. In order to prevent leakage of any water 80 which might accumulate in the chamber 14, the lower or intake end of the air passage 17 is equipped with a ball check valve 21, adapted to permit the entrance of air in an upward direction but to preclude reverse flow of liquid from the passage. 85

A valve 22 opening upwardly into the chamber 14 is adapted to close both of the 90 passages 15 and 17, the valve being normally retained against its seat by a coiled expansion spring 23 interposed between the upper face of the valve and a cap 24 forming a closure for the upper end of the chamber 14. The stem of the valve 22 extends downwardly into the receptacle 13, 95 where it engages the upper face of a guide plate 25 carried by and serving as a guide for a thermostatic element 26 disposed within the chamber. This element may be of any preferred construction, but in the present instance is shown as of the expansible bellows type filled with an expansible liquid so that when the temperature of the water 100 in the receptacle rises, upward expansion of the element will lift the valve 22 from its seat, thereby establishing communication between the chamber 14 and the receptacle 13 through the passage 15, and also communication between the chamber and atmosphere through the passage 17.

The lower end of the receptacle 13 is 110 closed by a cap or plug 27 which carries an adjustable supporting screw 28 upon

which the bottom of the thermostatic element 26 rests. By adjusting this screw which is held in adjusted position by a lock nut 29, the thermostatic element may 5 be adjusted to open the valve 22 or permit it to close at any desired predetermined temperature.

The chamber 13 is filled with water from the water cooling system and the water 10 circulates through the chamber so that the thermostatic element is subjected to the same temperature as the temperature of the cooling water leaving the engine. A pipe 31 connects the receptacle with the outlet cir- 15 culating pipe 11 from the engine block and another pipe 32 connects the receptacle with the intake pipe 9 leading from the bottom of the radiator to the engine block. When the engine is in operation, the water will 20 flow into the receptacle 13 through pipe 31 and outwardly therefrom through the pipe 32, thus maintaining a circulation of water through the receptacle so that the thermo- 25 static element is subjected to the temperature of the water leaving the engine.

Within the lower portion of the chamber 14, there is disposed a removable ring 33 (Fig. 5) upon which is mounted an atomizing nozzle 34 positioned to deliver into 30 a passage 35 which is connected by a pipe 36 with the intake manifold 7. A suction, therefor, is exerted through this pipe upon the nozzle 34 so that air and water in the chamber 14 will be withdrawn therefrom, 35 the water through the nozzle, and the air around the nozzle by which the air and water are mixed so as to provide a vapor which is delivered into the manifold.

In order that the supply of vapor to the 40 manifold may not be started until the engine has attained a predetermined speed, I have interposed in the passage 35 a shut-off plug valve 37 provided at one end with an arm 38 which is connected by a link 39 45 with the throttle control rod 8. When the throttle rod is positioned to close or substantially close the throttle of the engine, the valve 37 will be closed and the supply of vapor to the manifold will be shut off. As 50 the throttle is gradually opened through manipulation of the rod 8, the valve 37 will correspondingly open and when the engine is running at full speed, the valve 37 will be fully opened to deliver the maximum 55 of vapor to the manifold. In order to prevent the passage 15 and the nozzle 34 from becoming clogged with sediment or other solid particles which might enter the receptacle 13, we have interposed in the upper 60 portion of the receptacle 13, a mesh screen 41, as shown on the drawings.

To insure the proper distribution of the vapor within the manifold, we prefer, instead of admitting it directly through a 65 single opening in the manifold wall, to

provide the delivery end of the pipe 36 with a nozzle 42 (Fig. 6) having a series of apertures through which the vapor is discharged into the manifold. Connection between the pipe 36 and the manifold may be established through a coupling member 43 of any preferred construction.

In the operation of our invention, assuming that the engine is cold, the thermostatic element 26 will be contracted and the valve 22 seated to close the passages 15 and 17. The disc 25 serves as a guide to maintain the thermostatic element in upright position. If the engine is now started, communication between the humidifier and the manifold will remain shut off until the throttle has been opened a sufficient distance to open the valve 37. If this valve is opened before the engine has heated up to a predetermined temperature, no vapor will be delivered to the manifold since the passages 17 and 15 are still closed by the valve 22. As the cooling water heats up, however, and circulates through the receptacle 13, as previously explained, the thermostatic 90 element 26 will expand, thereby lifting the valve 22 from its seat against action of the spring 23, and opening passages 15 and 17 so that air from the outside and water from the receptacle 13 will be delivered into the 95 chamber 14. This air and water will be mixed by the nozzle 34 and delivered as a vapor to the pipe 36 by which it is conducted to the manifold, where it is further vaporized and distributed within the manifold through the nozzle 42.

It is believed that the construction, operation and many of the advantages of our invention will be understood and appreciated from the foregoing without further description, and while we have shown and described a preferred embodiment, obviously the details of construction may be varied within wide limits without departing from the essence of the invention as set forth in 110 the following claims.

We claim:

1. An humidifier for internal combustion engines comprising, a water chamber, a vaporizing chamber adjacent said water chamber, a passage connecting said chambers, an air passage entering said vaporizing chamber and means in said water chamber controlled by the temperature of the engine to open and close both of said passages.

2. An humidifier for internal combustion engines comprising, a water chamber, a vaporizing chamber adjacent said water chamber, a passage connecting said chambers, an air passage entering said vaporizing chamber, means in said water chamber controlled by the temperature of the engine to open and close both of said passages and manually adjustable water flow regulating means in said connecting passage.

3. An humidifier for internal combustion engines comprising, a water chamber, a vaporizing chamber adjacent said water chamber, a passage connecting said chambers, an air passage entering said vaporizing chamber, means in said water chamber controlled by the temperature of the engine to open and close both of said passages and manually operable air flow regulating means in said air passage. 70
4. An humidifier for internal combustion engines comprising, a water chamber, a vaporizing chamber adjacent said water chamber, a passage connecting said chambers, an air passage entering said vaporizing chamber, means in said water chamber controlled by the temperature of the engine to open and close both of said passages, manually adjustable water flow regulating device in said connecting passage and manually operable air flow regulating means in said air passage. 75
5. A humidifier for gas engines, comprising a casing having a water receptacle in its lower portion, a chamber above said receptacle, a passage connecting said receptacle and chamber, a valve controlling said passage, a thermostatic element in the receptacle for actuating the valve, an adjustable needle for regulating the size of said passage, and an atomizing nozzle communicating with said chamber. 80
6. A humidifier for gas engines, comprising a casing provided with a water receptacle and a chamber thereabove, a passage establishing communication between said receptacle and said chamber, a needle adjustably controlling the size of the passage, a second passage establishing communication between said chamber and atmosphere, a needle controlling the effective area of said second passage, a valve for shutting off both of said passages, a thermostatic element in said receptacle for controlling said valve, and an atomizing nozzle communicating with said chamber whereby air and water delivered to said chamber through said passages are mixed. 85
7. A humidifier for gas engines, comprising a casing provided with a water receptacle and a chamber, a passage connecting said receptacle and chamber, a valve controlling said passage, a thermostatic element adapted to be actuated by the heat of the engine for opening said valve when the temperature of the engine reaches a predetermined point, manually adjustable means for regulating the flow through said passage, means for atomizing the water delivered to said chamber through said passage, means for conducting said atomized mixture to the intake manifold of an engine, and means for controlling the vapor supply. 90
8. The combination with a gas engine, comprising an intake manifold, a water
- cooling system and a throttle control, of a water receptacle connected with the cooling system, an atomizing device connected with said manifold, means controlled by the temperature of the water in said receptacle for regulating the admission of water and air to said device, adjustable means for regulating the amount of water admitted, and means actuated by said throttle control for regulating the supply of vapor from said device to said manifold. 95
9. The combination with a gas engine including a water cooling system, an intake manifold and throttle control, of a water receptacle adapted to be connected to said cooling system, an atomizing nozzle, passages leading from said nozzle to said receptacle and to atmosphere respectively, a valve for closing both of said passages, a thermostatic element in said receptacle for actuating said valve, a valve interposed between said nozzle and said intake manifold, and an operative connection between said last mentioned valve and said throttle control. 100
10. The combination with a gas engine including a water circulating system, an intake manifold and a throttle control, of a humidifier comprising a water receptacle, a chamber above said receptacle, a passage connecting said receptacle with said chamber, an air passage leading to the chamber, a valve for closing said passages, a thermostatic element in said receptacle controlling said valve, a connection between said chamber and said manifold, a valve in said connection, and means whereby said valve is actuated from said throttle control. 105
11. A humidifier for gas engines, comprising a casing providing a water chamber adapted to be connected with the cooling system of an internal combustion engine, a vapor chamber adapted to be connected with the intake manifold of such engine, a water passage communicating with both chambers, an air inlet passage, a valve for closing both of said passages, a thermostat in said water chamber and connected to said valve, and means for regulating the action of said thermostat. 110
12. In combination with an internal combustion engine, fuel intake means, fuel humidifier means connected therewith and means operative to humidify the fuel in substantially direct proportion to engine speed and temperature. 115
13. In combination with an internal combustion engine, fuel intake means, means in operative relation to said intake means to humidify fuel therein and means automatically operative after a predetermined engine speed and temperature have been reached to thereafter substantially proportionately increase the fuel humidity in accordance with the speed and temperature. 120
14. In combination with an internal com-

bustion engine, fuel supply means, fuel humidifying means and humidity regulating means responsive to a predetermined temperature to humidify the fuel in substantially direct proportion to the engine speed.

15. In combination with an internal combustion engine, fuel intake means, fuel

humidifying means including an auxiliary water circulating system connected to said intake means, and means responsive to the temperature of the water in said auxiliary system and to a predetermined engine speed to vary the fuel humidity.
